UNITED STATES PATENT OFFICE.

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

YARN GUIDE FOR KNITTING MACHINES.

Application filed May 21, 1927. Serial No. 193,279.

The invention relates to yarn guide fingers. I have shown the invention carried out in connection with a yarn guide adapted to a full fashioned machine of the Cotton type.

5 The invention is shown in the accompanying drawing, in which:

Figure 1 is a front view of the improved yarn guide.

10 Fig. 2 is an enlarged view of the lower end of Fig. 1.

Fig. 3 is a bottom plan view of Fig. 2.

Fig. 4 is a view of one of the guide tubes detached.

15 In these drawings 1 indicates a yarn guide adapted to be attached to the reciprocating carrier bar of a Cotton frame. Its lower end is split and spring tempered. The opposing faces 2 of the lower split end of the yarn

20 guide are grooved as shown and these grooves have inclined bottoms presenting jointly a receiving socket formation which is flared towards its upper end. In this socket-like formation a yarn guide tube 3 is mounted. It is tapered to fit the recess between the ends of the split guide and as its upper end is of a diameter larger than its lower end, it will be retained in place

25 merely by the grip of the ends 4, 4 of the split member thereon. It can not become displaced nor dislodged from between these ends by a lengthwise movement because of

30 its upward flared formation or its general taper, it being understood that the said tube may be tapered from end to end or said taper may extend only part way of the length of the tube. In order to place the tube in position it is pressed laterally between the jaws 4, 4 of the split member.

35 These jaws will spring apart sufficiently to allow the tube to be snapped into place, and a suitable implement like a pair of pliers may be employed to snap the tube into position. The jaws 4, 4 have an enlarged recess

40 between their upper ends at 5, rendering the jaws more resilient by reducing the thickness of the upper ends of said jaws.

45 There is a groove 6 extending vertically along the front face of the guide for the passage of the yarn to the tubular insert guide piece 3. This tubular member 3 projects below the lower end of its holder.

50 When a tube 3 becomes worn it is removed and its place is taken by a new tube. In placing a new tube in position it is forced

between the spring jaws 4, 4 by pressure exerted in a direction laterally of the main body of the guide. That is to say, the new tube is placed sidewise against the old tube and when pressure is applied to the new tube 60 it is forced in between the jaws and the old tube is forced out from between the jaws.

The renewal can be made quickly, and no fastening means is necessary to hold the tube in place, the spring grip of the jaws 65 and the tapered form of the seat between the jaws being all that is necessary to insure the holding of the tube in place. At its upper end the tube abuts the shoulders 7 forming the upper wall of the socket or 70 grooves between the spring jaws 4, 4.

In a previous form of guide, a removable cylindrical tube has been employed which is soldered in place between flat faced jaws. When this is to be renewed, the solder must 75 be melted and the new tube inserted and resoldered. This takes much time. Renewal of the guide tube is necessitated by the wear of the yarn. When silk is used the guide tube is soon cut by the continued action of 80 the silk yarn thereon and renewal of the tube then becomes necessary.

I claim:

1. A yarn guide having spring jaws, a guide tube snapped into place between said 85 jaws and shaped to prevent endwise removal, substantially as described.

2. A yarn guide having spring jaws with grooves in the opposing faces of said jaws, and a guide tube snapped laterally into 90 place between said jaws and flared externally to prevent longitudinal displacement or removal, substantially as described.

3. In combination in a yarn guide for full fashioned knitting machines, a member having spring jaws with grooves in their opposing faces, said grooves being enlarged at one point and presenting shoulders at their upper ends, and a yarn guide tube held between said jaws in the grooves and against 100 the shoulders, and having an enlarged portion to fit the enlargement of the grooves to prevent lengthwise dislodgment of the tube, substantially as described.

4. A yarn guide having spring jaws, a 105 guide tube snapped into place between said jaws, said jaws and tube having coating surfaces shaped to prevent endwise removal of said tube in both directions.

5. A yarn guide consisting of a depending 110

plate like member comparatively thin throughout its lower portion and terminating in spring jaws at its lower end, and a guide tube located between said spring jaws and disposed with its axis intermediate the front and rear faces of the jaw portion of said thin plate-like member.

6. A yarn guide having spring jaws hav-

nig a normal tendency to spring towards each other, a guide tube between said jaws, with means for holding said tube in said jaws against longitudinal displacement in either direction.

In testimony whereof, I affix my signature.

KENNETH HOWIE.
